UNITED STATES PATENT OFFICE.

EDSELL TOTMAN, OF LA GRANGE, ILLINOIS.

DOVETAILING-MACHINE.

SPECIFICATION forming part of Letters Patent No. 374,018, dated November 29, 1887.

Application filed June 21, 1886. Serial No. 205,745. (No model.)

To all whom it may concern:

Be it known that I, EDSSELL TOTMAN, of La Grange, in the county of Cook and State of Illinois, have invented certain new and useful 5 Improvements in Dovetailing-Machines; and I do hereby declare that the following is a full, clear, and exact description thereof, reference being had to the accompanying drawings, and to the letters of reference marked thereon, 10 which form a part of this specification.

This invention relates to that class of machines employed for cutting longitudinal dovetailed grooves in boards or strips, the means herein described being more particularly intended for use in machines used in manufacturing what is known as "combined sheathing and lathing," or sheathing strips grooved upon one or both faces to afford a hold for plastering.

The invention consist in the matters herein- 20 after described, and pointed out in the appended claims.

In the accompanying drawings, illustrating my invention, Figure 1 is a side elevation of a device embodying my invention, shown as secured upon the frame of a planing-machine, and illustrating the belt-connection for driving the dovetailing device. Fig. 2 is a side elevation, upon an enlarged scale, of the dovetailing device shown in Fig. 1. Fig. 3 is a detail sectional view through the arbor or mandrel of one of the saws and its support. Fig. 4 is a detail side elevation of a casting for supporting the saw-mandrels. Fig. 5 is a detail section of the same, taken upon line xx , Fig. 4.

As illustrated in the said drawings, A is a bed or frame upon which the dovetailing devices are supported, said frame, as herein shown, being that of a "planing matcher," or machine for making tongues and grooves, 30 said dovetailing device being conveniently attached upon the frame of the machine, so as to operate upon the strip to be dovetailed after the latter has been reduced to suitable shape by the operation of the machine.

B B' are the grooving-saws, arranged obliquely with reference to one another, with their lower parts in position to form opposite sides of a dovetailed groove, as clearly shown in Fig. 2, and in the manner common heretofore in machines of this class.

C C' are the mandrels, to which the saws B B' are respectively attached. Said mandrels, instead of being arranged to extend in oppo-

site directions from the saws, as common heretofore, are located both at the same side of the 55 saws, so that the belt-pulleys D D' thereon are both brought to the same side of the machine.

E E' E' are bearing-boxes for the mandrels C C', respectively, each mandrel being provided with two of said bearing-boxes, ar- 60 ranged near its ends, and secured to plates or castings F F', which latter are bolted to a cast- 65 ing, G, secured to the frame A and formed to sustain the castings F F' and the mandrels supported thereby at opposite inclinations. 70 The bearing-boxes E E' are secured to the plates F F' by means permitting a bodily lateral adjustment of the shaft in a vertical plane, the said boxes being herein shown, Figs. 2 and 3, as secured to the castings F F', which rest 75 upon the casting G, whereby the saw-arbors and their bearings may be adjusted in the man- ner above-mentioned. This adjustment of the mandrel-bearings is mainly for the purpose of ad- 80 justing the saws vertically to make deeper or 75 shallower grooves. The said arbor-bearings are, however, as herein shown, made inde- 85 pendently adjustable to enable the inclination of the saws to be changed to make the sides of the grooves more or less inclined, as desired. 85

In the particular construction herein illus- 85 trated the bearings E E' are provided with flat surfaces in contact with the plates F F', and said bearings are secured by a single bolt, e, 90 whereby the bearings may be turned upon their seats when the inclination of the man- drel is changed by changing the bodily posi- 95 tions of the bearings, as above described. The seats upon the plates F F', against which the bearings E E' rest, are shown in the drawings 90 as made with raised parts or ribs $f^2 f^2$, to form the bearing-surfaces; but this construction is obviously not essential.

The casting G, by which the plates F F' are sustained, is formed or provided with opposite 95 inclined seats or bearing-surfaces G' G'', adapt- 100 ed to receive and sustain the plates F F', re- spectively, as clearly shown in Figs. 2, 3, 4, and 5. The said plates F F' are adjustably se- 105 cured upon the inclined seats G' G'' by means permitting a longitudinal adjustment of the said plates, whereby the relative position of the saws may be changed to produce grooves of greater or less width, as desired.

In the particular construction of the parts 105 herein illustrated as one convenient form

thereof the plates or castings F F' are provided at their lower margins with laterally-extending flanges forming flat plates F² F³, adapted to rest upon the inclined seats G' G² 5 of the casting G, said seats being preferably provided with rabbets g g' g', receiving the edges of the plates F² F³ and serving to hold the plates F F' from displacement laterally. The attaching devices for securing the plates 10 F F' to the casting G, herein illustrated, consist of headed bolts H H', inserted through the flat plates F² F³ of the castings F F' and passing through slots g² g³ in the said casting G.

The casting G, provided with inclined seats 15 G' G², as above described, may be made or formed in its other parts in any shape or manner found desirable or convenient, and said casting may be secured to a machine frame or bed in any convenient manner, or in some 20 cases it may be independently supported and itself form the frame of a dovetailing-machine.

As herein shown, the parts of the casting G upon which the seats G' G² are formed are connected by a vertical web, g', and flanged 25 webs g⁵ g⁶ are provided at the lateral margins of the casting to form bearing-faces which rest upon the top of the frame or table A.

Any suitable guide and feed devices may be used for the strips to be grooved, a supporting-plate, I, being herein shown for sustaining 30 the strip in its passage beneath the saws, and a lateral guide, I', being provided for the outer edge of the strip. I have herein shown a top guide, I², as secured to the lateral guide I', 35 and extending over the top of the strip to hold the latter from rising, the guides I' I² being shown as secured to the supporting-plate I by a bolt, i, passing through a slot in the guides I' I², whereby the latter may be adjusted toward and from the saws, as may be desired, 40 for strips of different widths. The strip is, as herein illustrated, guided at its side opposite to the guide I' by contact with the inner vertical face of the casting G.

An important and principal advantage 45 gained by the location of both of the saw-mandrels upon one side of the machine is that said mandrels may, by this construction, be driven by a single driving-belt trained over the belt-pulleys D D' upon the mandrels and around suitable driving and guide pulleys. An improved construction in the driving devices is herein illustrated, in which J is a driving-pulley located at the end of the machine-frame A 50 opposite to that at which the dovetailing devices are placed; K, an idler located between the pulley J and the said dovetailing devices, and L a belt which passes from the pulley J to the pulley D of the upwardly-inclined saw-mandrel, thence over the idler K, and from said idler over the pulley D' of the downwardly-inclined saw-mandrel back to the pulley J.

The belt-pulleys D and D', driving-pulleys, and idlers will be relatively so located that the 65 belt will remain upon the said pulleys notwithstanding the twist in the belt occasioned

by the inclined position of the saw-mandrels. The latter are, as shown, preferably extended for some distance exterior to their outer bearings to enable the pulleys D and D' to be adjusted thereon as found necessary to bring them in proper position with relation to the idler and drive-pulley.

I am aware that it has been proposed heretofore to drive two spindles arranged parallel with each other by means of a drive-pulley and an idler. I am not aware, however, that it has ever been proposed heretofore to employ in connection with two saw-mandrels arranged obliquely with reference to each other 70 and belt-pulleys upon the mandrels an idler located between the pulleys upon the saw-mandrels and the drive-pulley with its axis parallel with that of the drive-pulley. A construction of this kind is therefore herein set 75 forth in the appended first claim as part of my invention.

I claim as my invention—

1. In a dovetailing-machine, the combination, with two saws arranged obliquely with 80 reference to each other, of mandrels for the saws located at the same side of the latter, belt-pulleys upon the said mandrels, a drive-pulley the axis of rotation of which is located in a plane parallel with planes passing through 85 the axes of the saw-mandrels, an idler located between the pulleys upon the saw-mandrels and the said drive-pulley, the axis of said idler being parallel with that of the drive-pulley, and a belt passing over the drive-pulley, the idler, 90 and both mandrel-pulleys, substantially as described.

2. The combination, with two saws arranged obliquely with reference to each other, of mandrels for the saws, both located at the same 95 side of said saws, plates, as F F', provided with bearings for the mandrels, and a part or casting, as G, supporting said plates F F' and provided with oppositely-inclined seats for the said plates F F', said plates being adjustably 100 secured upon the said seats, substantially as described.

3. The combination, with two saws arranged obliquely with reference to each other, of mandrels for said saws, both located at the same 115 side of the saws, plates, as F F', sustaining the mandrels, bearings, as E E', for the opposite ends of the mandrels, attached to the plates F F' and independently adjustable thereon, a part or casting, as G, sustaining the plates F F', and 120 provided with two oppositely-inclined seats for the said plates, and means adjustably securing said plates to the said casting, substantially as described.

In testimony that I claim the foregoing as my 125 invention I affix my signature in presence of two witnesses.

EDSELL TOTMAN.
